UNITED STATES PATENT OFFICE.

ABRAM N. PASMAN, OF WATERBURY, CONNECTICUT, ASSIGNOR TO SCOVILL MANUFACTURING COMPANY, OF WATERBURY, CONNECTICUT, A CORPORATION OF CONNECTICUT.

SUPPLY, WASTE, AND OVERFLOW FITTING.

Application filed October 12, 1926. Serial No. 141,170.

My present invention relates to a supply, waste and overflow fitting so designed as to be employed in either the now prevalent enclosed piping constructions or in the open plumbing work heretofore used. The object of the invention is the provision of a fitting of this type associated with a bath tub, basin or other fixture in which the supply and overflow member are arranged in the wall of the fixture and through which the valve or stopper for the control of the passage of water through the waste pipe may be withdrawn when necessary for repairs or replacement or for other purposes, as will be hereinafter more particularly described.

In the drawing Figure 1 is a sectional elevation illustrating an apparatus in which my present invention is embodied.

Fig. 2 is a front elevation of the supply and overflow attachment, and

Fig. 3 is a view similar to Fig. 1 illustrating another form of the invention.

Referring to the drawing and particularly to Figs. 1 and 2, it will be seen that I have illustrated the invention in connection with a bath tub which is designated at 10, although it will be understood that the invention may be employed to equal advantage with basins or other similar fixtures. The invention furthermore, is illustrated with a tub, whether enclosed or otherwise, which is provided with an upper flange 11 terminating in the rim of the tub. The tub is also provided with the usual waste opening 12 to which is connected a waste pipe 13 leading to a T fitting 14 which is connected to a soil pipe 15 in the usual manner. Within the T connection 14 there is a cylindrical stopper or valve 16 and the T connection interiorly is provided with seats 17 and 18 against which the respective upper and lower portions 19 and 20 of the stopper are adapted to bear to close the communication between the waste pipe 13 and the soil pipe 15. Extending upwardly from the T connection 14 there is an overflow pipe 21.

Fitted to the overflow pipe 21 at the upper end thereof there is a supply and overflow member 22. This may be connected to the overflow pipe in any suitable manner. The supply and overflow member 22 is made to include an inlet connection 23 to which there is secured a supply pipe 24 leading from hot and cold water supplies controlled

by valves or faucets in the usual manner. The inlet connection 23 forming part of the supply and overflow member extends into the interior of this member and therein forms a socket 25 for the reception of the inner end of a spout member 26. This spout member 26 is adapted to extend through an opening 27 provided therefor in the wall of the tub 10. There are ports 28 in the walls of the spout member and the inlet connection 23 whereby communication is made between the chamber in the inlet connection and the chamber 29 in the spout member. The spout member is provided with a discharge nozzle 30 which is in communication with the chamber 29 whereby water permitted to flow from the supply pipe 24 passes through the inlet connection to the chamber 29 in the spout member and thence through the nozzle 30 to the tub 10 or other fixture.

The spout member 26 is provided with a flange 31 preferably having the outer portion thereof turned inwardly and so placed as to be adapted to bear against the outer surface of the tub or other fixture. In the lower portion of this flange there are holes or openings 32 through which when the water in the tub reaches a predetermined height it flows therefrom through the opening 27 and thence by way of the supply and overflow member 22 to the overflow pipe 21. The spout member 26 is preferably provided with oppositely disposed bosses 33 by means of which and screws 34 passing therethrough and into lugs 35 on the inlet connection 33 it is secured in position. As illustrated, a tight joint is made at the outer surface of the tub by means of a gasket 36 and an annular member 37 which is angular in cross section forming a seat for the gasket and preventing the spread thereof beyond predetermined limits. Also as illustrated, a gasket 38 may be employed between the outer surface of the inlet connection 23 and a flange on the outer wall of the spout member 26. Interiorly the spout member is provided with a partition wall 39 providing a chamber for the reception of a stem 40 which passes therethrough. At the inner end of this stem 40 there is a crank 41 terminating in a crank pin 42, while at the opposite or outer end of the stem which extends beyond the spout member a handle 43 is secured by a screw 44 or otherwise. In oppositely dis-

posed positions the outer face of the spout member 26 is provided with notches 45 adapted to be engaged by ribs 46 provided for this purpose on the inner face of the hub of the handle so that in turning the handle the ribs may snap into and out of these notches within which they are normally maintained in position with the handle either up or down by means of a spring 47 extending between the crank end 41 of the stem and the adjacent end wall of the spout member. As will be understood, this provides for a slight longitudinal movement of the stem which, however, does not affect the function thereof in operating the stopper as hereinafter described. The crank pin 42 fits and operates in a slot provided therefor in a link 48 which is pivotally connected as indicated at 49 to a socket link 50 within the supply and overflow member 22. This socket link 50 is connected by chain links 51, 52 and a bale or cross bar 53 to the stopper or valve member 16.

The parts of the apparatus as hereinbefore described are in their normal positions as illustrated in Fig. 1 in which as will be seen the handle 43 is yieldingly maintained in place above the outer portion of the spout member 26, and the crank arm 41 in its raised position in which through the links of the chain or equivalent devices the stopper or valve 16 is raised. Now as will be understood, by moving the handle 43 to the oppositely disposed position the crank arm 41 will be turned to its downward position in which the stopper or valve 16 is lowered by gravity to the position shown in dotted lines to close or shut off communication between the waste pipe 13 and the soil pipe 15 whereby the water flowing into the tub or other fixture will be retained therein for the purposes of bathing or otherwise. Naturally, when the handle is returned to its initial position the stopper will be raised and the water permitted to flow from the tub by way of the waste pipe 13 to the soil pipe 15. It is further to be noted that the stem 40 passes through the spout member and the diameter of the inner end of the spout member and the socket into which it fits in the inlet connection is such that by the removal of the spout member the chain and the stopper or valve may be completely removed through the socket opening for the purposes of re-placing the stopper or valve or for repairs as may be necessary.

In the form of the invention shown in Fig. 2 the stem and crank for operating the stopper are so arranged that they pass directly into the overflow portion of the supply and overflow member through which instead of through the socket of the spout member these parts and the chain and stopper may be removed. In this construction the supply and overflow member is indi-

cated at 54. This is suitably connected to the upper end of the overflow pipe 55. The supply and overflow member 54 in this construction is provided with an inlet connection 56 to which is secured a supply pipe 57. The spout member 58 is provided with an internal nozzle 59 which is adapted to extend through the upper portion of an opening 60 in the wall of the tub and to engage with a socket 61 provided for this purpose in the wall of the inlet connection 56. In this device as in the other form of the invention the spout member 58 is provided with bosses by which and by suitable screws 62 cooperating with lugs 63, the spout member is secured in position. The chamber in the spout member is designated by 64 and this communicates with a discharge nozzle 65 by means of which water admitted to the supply pipe 57 flows through the inlet connection 56 to the chamber 64 and thence through the nozzle 65 to the tub or other fixture. The spout member 58 in this construction is provided with an internal wall 66 making provision for a chamber 67 through which a stem 68 extends. This stem 68 is provided with a collar 69 and fitted with a spring 70 extending between the collar and the adjacent inner surface of the spout member whereby the ribs 71 provided on the inner face of the hub of the handle 72 are normally maintained in place in notches 73 in the outer face of the extremity of the spout member 58. The inner end of the stem 68 is provided with a crank 74 and connected to the stopper chain in the same manner as that hereinbefore described in connection with the other form of the invention. In this structure also, the spout member 58 is made to include a flange 75 which bears against the outer surface of that portion of the tub adjacent the overflow opening 60 therein and the lower portion of the flange is provided with overflow holes 76. A tight joint between the supply and overflow member 54 and the outer face of the tub may be made by means of a gasket 77 and the annular seat 78 employed in conjunction therewith in the same manner as that hereinbefore described in connection with the other form of the invention. Furthermore, in the construction as shown in Fig. 3, a gasket 79 may be fitted in the socket 61 so as to engage the inner or end portion of the nozzle 59 to make a tight joint therewith, although as will be understood, it is not essential to make an absolutely tight joint between these parts because any water which may leak by them will find its way to the overflow pipe.

In the form of the invention shown in Fig. 3, the spout member and the parts associated therewith may be removed and in so doing the chain and stopper or valve may be withdrawn through the overflow

portion of the supply and overflow member, the parts being designed for this purpose.

I claim as my invention:

1. In a fitting of the class described, a waste pipe, a stopper therein, a supply and overflow member connected to the waste pipe, a spout member removably attached to the supply and overflow member, and means associated with the spout member for operating the stopper in the waste pipe, the said stopper being removable through the supply and overflow member when the said spout member is detached.
2. In a fitting of the class described, a waste pipe, a stopper therein, a supply and overflow member connected to the waste pipe, a spout member removably attached to the supply and overflow member, a stem extending through the said spout member, and a connection between the said stem and stopper for operating the latter by the former, the said stopper being removable through the supply and overflow member when the spout member is detached.
3. In a fitting of the class described, a waste pipe, a stopper therein, a supply and overflow member having an overflow chamber in communication with the waste pipe and an inlet connection extending into the said overflow chamber, a spout member making communication with the said inlet connection and being removably attached to the said supply and overflow member, and means associated with the said spout member for operating the stopper in the waste pipe, the said stopper being removable through the said supply and overflow member when the spout member is detached.
4. In a fitting of the class described, a tub, a waste pipe leading therefrom, a stopper in the waste pipe, a supply and overflow member connected with the waste pipe, a spout member adapted to extend through an opening in the wall of the tub and to be removably attached to the said supply and overflow member, and means associated with the spout member for operating the stopper in the waste pipe, the said stopper being removable through the supply and overflow member when the spout member is detached.
5. In a fitting of the class described, a tub, a waste pipe leading therefrom, a stopper in the waste pipe, an overflow pipe connected to the waste pipe, a supply and overflow member connected to the overflow pipe, a spout member extending through an opening in the wall of the tub and adapted to be removably attached to the said supply and overflow member, and means associated with the spout member for operating the stopper in the waste pipe, the said stopper being removable through the said supply and overflow member when the spout member is detached.
6. In a fitting of the class described, a tub, a waste pipe leading therefrom, a stopper in the waste pipe, an overflow pipe connected to the waste pipe, a supply and overflow member connected to the overflow pipe, a spout member extending through an opening in the wall of the tub and engaging with the said supply and overflow member, means for detachably connecting the spout member to the said supply and overflow member, a stem passing through the said spout member, and means connecting the stem with the said stopper whereby the latter is operated by the former, the said stopper being removable through the said supply and overflow member when the said spout member is detached.
7. In a fitting of the class described, a tub, a waste pipe leading therefrom, a stopper in the waste pipe, an overflow pipe connected to the waste pipe, a supply and overflow member connected to the overflow pipe and having an overflow chamber and an inlet connection extending into the said overflow chamber, a spout member adapted to extend through an opening provided in a wall of the tub and having an apertured flange adapted to bear against the outer surface of the tub, the said spout member extending into a socket provided therefor in the said inlet connection within the said overflow chamber in the supply and overflow member, means for removably attaching the spout member to the said supply and overflow member, a stem passing through the said spout member, a handle at the outer end of the stem for operating the same, and a connection between the inner end of the stem and the said stopper for moving the stopper to and from a seated position, the said stopper being removable through the socket in the inlet connection, in which the said spout member is seated, when the said spout member is detached.

Signed by me this 4th day of Oct., 1926.

ABRAM N. PASMAN.
